PAGE 2

FIG. 2

FIG. 3

FIG. 4

FIG. 5

FIG. 6

FIG. 7

FIG. 1 is an isometric view of a pneumatic power tool for applying fasteners showing my new design.

FIG. 2 is a side elevational view thereof; the opposite side being substantially the same in appearance;

FIG. 3 is a bottom plan view thereof;

FIG. 4 is a top plan view thereof;

FIG. 5 is an elevational view taken from the left side of FIG. 2;

FIG. 6 is the same as FIG. 5, but with the element shown in broken lines omitted for purposes of illustration;

FIG. 7 is an elevational view taken from the right of FIG. 2.

The essential features of my design reside in the full line portion of the drawings.

I claim:

The ornamental design for a pneumatic power tool for applying fasteners, as shown and described.
